CLAIM

The ornamental design for a portable power station as shown and described.

DESCRIPTION

FIG. 1 is a front elevational view of a portable power station showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a front view thereof in an alternative configuration; and,

FIG. 9 is a second perspective view thereof in an alternative configuration.

The broken lines shown in portable power station form no part of the claimed design.
